(57) CLAIM

The ornamental design for a beverage vessel with lid, as shown and described.

DESCRIPTION

FIG. 1 is a perspective view of a beverage vessel with lid in a closed configuration with the pivoting carrying loop extended outwardly showing our new design;

FIG. 2 is a rear elevational view thereof;

FIG. 3 is a left side elevational view thereof;

FIG. 4 is a front elevational view thereof;

FIG. 5 is a top plan view thereof;

FIG. 6 is a bottom plan view thereof; and,

FIG. 7 is an exploded view thereof.

The broken lines in the drawings depict portions of the beverage vessel with lid that form no part of the claimed design.
